US00D840977S

(12) **United States Design Patent** (10) **Patent No.:** **US D840,977 S**
Pu (45) **Date of Patent:** **** Feb. 19, 2019**

(54) **HEADSET**

(71) Applicants: **Guizhou Laccess Technology Industry Ltd.**, Guizhou (CN); **Dongguan Laccess Electronic Technology Ltd.**, Dongguan (CN)

(72) Inventor: **Cheng-Gang Pu**, Dongguan (CN)

(**) Term: **15 Years**

(21) Appl. No.: **29/613,214**

(22) Filed: **Aug. 8, 2017**

(30) **Foreign Application Priority Data**

May 12, 2017 (CN) 2017 3 0175305

(51) LOC (11) Cl. **14-01**

(52) U.S. Cl. **USPC D14/206**

(58) **Field of Classification Search**

USPC D14/206, 205, 225, 226, 188, 192, 371; D29/112; 2/209; 181/129, 130, 135; 379/430, 431; 381/380, 381, 370, 374, 381/375, 376-379, 385; 455/90, 3, 575.1, 455/569.1

CPC H04R 1/1066; H04R 1/1016; H04R 5/033; H04R 25/00

See application file for complete search history.

Primary Examiner — Paula Allen Greene

(74) Attorney, Agent, or Firm — Prakash Nama; Global IP Services, PLLC

(57) **CLAIM**

The ornamental design for headset, as shown and described.

DESCRIPTION

FIG. 1 is a front elevational view thereof;
FIG. 2 is a rear elevational view thereof;
FIG. 3 is a left side elevational view thereof;
FIG. 4 is a right side elevational view thereof;
FIG. 5 is a top elevational view thereof; and,
FIG. 6 is a bottom elevational view thereof.

1 Claim, 6 Drawing Sheets
